DIGITAL CLOCK

Tomokazu Suzuki, Tokyo, and Jiro Ochiai, Yokohama,
Japan, assignors to Tamura Electric Works, Ltd.

Filed Feb. 25, 1974, Ser. No. 445,102

Term of patent 14 years

Int. Cl. D10—01

U.S. Cl. D10—15

FIG. 1

FIG. 2

FIG. 3

FIG. 4

FIG. 5

FIG. 6

FIG. 7

FIG. 8

FIG. 1 is a front elevational view of a digital clock showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a cross-sectional view as taken from line VI—VI of FIG. 1;

FIG. 7 is a front perspective view thereof;

FIG. 8 is a rear perspective view thereof.

We claim:

The ornamental design for a digital clock, as shown and described.
